C. L. GOODRUM,
TELEPHONE EXCHANGE SYSTEM
APPLICATION FILED DEC. 14, 1910

1,224,161

Patented May 1, 1917.

UNITED STATES PATENT OFFICE.

CHARLES LANE GOODRUM, OF URBANA, OHIO, ASSIGNOR, BY MESNE ASSIGNMENTS,
TO WESTERN ELECTRIC COMPANY, INCORPORATED, A CORPORATION OF NEW YORK.

TELEPHONE-EXCHANGE SYSTEM.

1,224,161.

Specification of Letters Patent.

Patented May 1, 1917.

Original application filed April 1, 1905, Serial No. 253,227. Divided and this application filed December 14, 1910. Serial No. 597,353.

To all whom it may concern:

Be it known that I, CHARLES LANE GOODRUM, a citizen of the United States, residing at Urbana, in the county of Champaign and State of Ohio, have invented certain new and useful Improvements in Telephone-Exchange Systems, of which the following is a specification.

My invention relates to telephone exchange systems and has for its object the improvements of said system particularly in the means employed for ringing or signaling a called subscriber; this application being a division of my pending application No. 253,227, filed April 1st, 1905.

In the accompanying drawing I have shown the invention as applied to an exchange in which automatic means for effecting a connection between a calling and called subscriber is employed; the particular means of setting up a connection from one subscriber to another, however, is not involved in this application, which as stated relates to signaling means and particularly to such as is generally known as automatic ringing.

The accompanying drawing which forms a part of the specification is a diagram showing my invention as applied to what is generally known as a three wire automatic common battery or central energy system.

In the drawing A and A' represent two subscribers' stations each equipped with the usual telephone outfit, and calling devices adapted to work in a common battery automatic system the calling devices being preferably such as have generally been known as the Strowger device which are adapted to send impulses from ground, first over one side of the line and then over the other to effect the operation of the switches.

Lines 1—2, 3—4 from these stations terminate at the exchange in suitable contacts to which connection may be made by means of switches, said lines also having connections to suitable switching mechanism by which connection may be made from one of said lines to the terminal contacts of other lines for conversation. For the purpose of illustration I have omitted the intermediate switches for establishing the connection between lines showing only what is known as the connector switch in connection with which I have shown my improved

mechanism for automatic ringing. It will be understood that any of the well known means for setting up connections between subscribers by means of various switches may be employed the means illustrated being adapted to be operated by the well known method of sending impulses from ground over the opposite sides of the subscriber's line to operate the switches in establishing a desired connection and for grounding both sides of the line for releasing and returning the switches to their normal positions.

In said drawings a represents the rotary shaft of a primary or selector switch having wipers a^2 and a^3 which through the operation of the switches (not shown) have been brought into contact with the line terminals m^1 of the connector switch, thus connecting the subscriber's line into the connector switch in the usual way. This shaft also has an operating circuit wiper a^4 which has been brought into contact with the terminal m^3 of the connector switch. This last mentioned wiper a^4 has been, in the operation of the switch mechanism, grounded, so that when it rests on the terminal m^3 a circuit is closed to the relay M^{19} over the following circuit: grounded wiper a^4 , contact m^9 , wire 95, connector switch wiper g^{30} , wire 96, switch relay M^{19} , wire 97, main battery B to ground. The relay M^{19} will thus be energized and in pulling up its armature operates a number of contacts one pair of which opens one side of the line 98—99 and another pair opens the other side 100—101, these lines being shown in heavy black and constituting the main lines or talking circuit when the connection is completed, said lines being thus held open during the subsequent operation of the switch or so long as the relay M^{19} is energized.

Operating relays M^{21} and M^{22} are normally connected to the opposite-sides of the line through normally closed contacts, battery and ground to respond to impulses that come over the opposite sides of the line from ground at the central station. The circuit of relay M^{21} being traced as follows: line 98, relay M^{21} , wire 102, contact 103, spring 104, wire 105, battery B and ground. The relay M^{22} being connected to line wire 100 as follows: wire 100, relay M^{22} , wire 106,

contact 107, spring 108, wire 109, contact 110, spring 111, wire 112, wire 105, to battery B and ground. Contacts 103—104 and 107—108 are controlled by relay M^{25} , while contacts 110—111 are controlled by relay M^{26} as hereinafter described. Relay M^{21} controls the spring 93, which engages contact 94 in the local circuit of the motor magnet M^{24} as follows: from battery B, wire 97, wire 92, spring 91, contact 90, wire 89, motor magnet M^{24} , wire 88, spring 93, contact 94, wire 87, spring 86, contact 85, wire 84, to the grounded pole of battery B, the contacts 90—91 being controlled by the relay M^{19} and contacts 85—86 are controlled by relay M^{23} as hereinafter described. Relay M^{19} being energized as before described the motor magnet circuit will be closed at contacts 90—91 and will also be closed at contacts 93—94 whenever the relay M^{21} is energized which would occur when No. 1 line is grounded at the calling subscriber's station. The motor magnet M^{24} is adapted to operate the rotary shaft g of the connector switch step by step in response to impulses received by the operating relay M^{21} in the usual way and carries the wipers g^1 , g^{21} — g^2 , g^3 — g^{30} . The wiper g^1 is connected to the ringing relay M^{26} in the manner hereinafter described. The wipers g^{21} and g^2 are the main line wipers and adapted when the switch is properly stepped around to rest upon the terminals of the called line. Said wipers being connected to the opposite sides 99 and 101 of the main line through contacts controlled by the relay M^{26} , wiper g^3 being the test or busy wiper. As the shaft g is rotated in stepping around the switch, the relay M^{19} which was previously energized by wiper g^{30} resting on a grounded contact would be held up over a local circuit including the contacts 115, 116, controlled by its own armature, the circuit being traced as follows: battery, wire 97, relay M^{19} , wires 113—114, contacts 115—116, wire 117, contacts 118—119, wire 120, to grounded battery. The contacts 118—119 are controlled by the relay M^{22} so that relay M^{19} will be energized so long as relay M^{22} remains in its normal position and the shaft g may be stepped around as necessary or until the wipers g^{21} , g^2 rest upon the contacts of the called subscriber's line. As soon as the shaft has been stepped around in response to the impulse over No. 1 side of the line with wipers g^{21} — g^2 resting on the terminals of the called subscriber's line a single impulse will be sent over the No. 2 side of the line following the usual so called Strowger method of sending impulses. This will energize the relay M^{22} and open the circuit of the relay M^{19} at contacts 118—119 and allow the said relay to assume its normal position, thus closing the lines 98—99, 100—101 which constitute the talking circuit and also

opening the motor magnet circuit. The talking circuit thus being connected through from the calling subscriber A to the called subscriber A¹ whose terminals are engaged by the switch wipers g^{21} — g^2 . It will be noticed that wire 117 which forms a part of the holding circuit for relay M^{19} is branched from wire 121 to the wiper g^3 and the contact m^{11} which is engaged by this wiper g^3 . In case a called subscriber is busy, wiper g^3 is grounded, so that in the event that the line called was busy M^{19} would not be deenergized by the operation of the relay M^{22} , but it would be held energized over the circuit before described; to wire 117 and thence by wire 121, wiper g^3 and grounded contact m^{11} . So long as relay M^{19} is kept energized the main or trunk lines 98—99 and 100—101 would be opened at the contacts controlled by this relay so that the calling subscriber could not be connected to a busy line.

Assuming, however, the line is not busy, the relay M^{19} will be deenergized by the pulling up of relay M^{22} under the influence of the single impulse coming over the No. 2 side of the line, thus connecting through the main or trunk lines 98—99 100—101 to form the talking circuit as before described, and at the same time breaking its own holding circuit at contacts 115—116. The relay M^{22} following the single impulse immediately becomes deenergized thus closing the contact 118—119 and grounding the contact m^{11} over the circuit including the wiper g^3 , wire 121—117, contacts 118—119, wire 120 and ground. This grounding of the contact m^{11} would operate the cut off relay (not shown) of the called subscriber in the usual way, to render the called subscriber clear from any connection with any individual or selector switch.

The calling subscriber now being connected to the called subscriber it remains necessary to supply generator current to the called line for the purpose of ringing or signaling the called subscriber. This is accomplished automatically by the wiper g^1 resting upon the contact m^{13} connected through interrupter m to ground. The wiper g^1 , as before stated, is connected to the relay M^{26} over the following circuit; the wiper g^1 , wire 75, relay M^{26} , wire 74, contact 73, spring 72, wire 71, contact 70, spring 91, wire 92, wire 97, battery and ground. The contact m^{13} being periodically grounded through the interrupter m periodically energizes the relay M^{26} which upon attracting its armature separates the contacts in the lines 99—100 which lead to the wipers g^{21} — g^2 and also closes the ringing circuit to one of the said wipers and which are now in connection as before stated, with the called subscriber's station. As the relay M^{26} is intermittently energized and deenergized by the grounded

interrupter, ringing, current will be applied periodically to the called subscriber until he answers. This circuit being as follows: grounded generator g^1 , wire 60, contact 61, spring 62, one side of the talking circuit 101, wiper g^2 , line wire 4, subscriber's ringer, condenser and ground.

It should be stated that the main or trunk lines forming the talking circuit are separated in the usual way at the connector switch by condensers as shown located in lines 98-100 thus conductively separating the called end of the line from the calling end of the line, and battery supply relays M^2 , M^2 are provided one of which is connected from one side of the line to battery and ground and the other to the other side of the line and ground thus bridging said relays on the called side of the line with interposed battery so that said relays will be simultaneously energized when the called end of the line is closed by the removal of the telephone from the hook. The circuit for the relay M^{25} is as follows: from line 98, wire 50, relay M^{25} , wire 51, wire 120, wire 84 to ground. The circuit for relay M^{27} is from line wire 100, wire 52, relay M^{27} , wire 53, wire 105, battery B and ground. When the called subscriber answers and closes his line by removing his telephone receiver these relays M^{25} and M^{27} being bridged across the called end of the line with interposed battery will be simultaneously energized and the current thus flowing over these lines will furnish talking battery to the called end of the line. The energization of relay M^{25} opens the circuits of relays M^{21} and M^{22} at back contacts 103, 104, 107, 108 through which the circuits for said relays (as before described) pass. The energization of relay M^{27} closes its forward contacts which closes the circuits of relays M^{18} and M^{20} which are thus bridged across the calling end of the line with interposed battery and thus furnishes talking current to the calling end of the line over the following circuit: battery B, wire 40, relay M^{20} , wire 41, contact 42, spring 43, wire 44, to main line 100, thence back through the switch wiper a^3 to the calling subscriber's station through the switch wiper a^2 , main line 98, wire 45, spring 46, contact 47, wire 48, relay M^{18} , wires 49, 51, 120, 84 to grounded side of battery. The energization of relay M^{20} also opens the circuit for relay M^{26} at back contact 72, 73, through which the circuit for said relay passes as heretofore described, thus deenergizing said relay cutting off the ringing current and closing the calling subscriber's end of the line and connecting through the main line or talking circuit as heretofore described.

In considering the operation it should be remembered that there is employed at the subscribers' stations the usual Strowger appa-

ratus the essential parts of which comprise the dial, receiver hook with contacts controlled by each arranged and operated as in the standard apparatus of this type, that is the receiver hook is adapted when released (by removing the receiver); to bridge the transmitter and receiver across the line through the induction coil and when the hook is depressed (by hanging up the receiver) it opens the said branch and in its downward movement closes both sides of the line to ground to effect the release of the switches. The contacts operated by the dial are so arranged that upon the first movement of the dial it opens the bridge of the subscribers' instruments, in its backward movement it grounds the No. 1 side of the line a number of times corresponding to the impulses to be transmitted, upon returning to normal it momentarily grounds the No. 2 side of the line to despatch a single impulse of current thereover and finally in arriving at its normal position closes the bridge for the talking instrument. The sub-station circuits of the apparatus of the Strowger system needs no explanation to those familiar with the art and it is understood that other means may be used for operating the system. The simplest form of apparatus comprises two push buttons for performing both movements attributed to the dial each arranged to ground one side of the line when actuated.

With the above understanding it will be seen that means have now been described by which a connection has been established between the calling and called subscriber, the called subscriber has been automatically signaled and has answered by removing his receiver and has thus supplied talking current to his own end of the line through the relays M^{25} and M^{27} which in operating have bridged the relays M^{18} and M^{20} across the calling end of the line with interposed battery thus supplying talking current to the calling end of the line.

For releasing the switches release relays are supplied in each of the switches which are adapted to be operated upon the operation of the release relay of the succeeding switch so that the switches will be released in the reverse order to that in which they are set up in the usual way. It will be only necessary to describe the means for operating the release relay M^{23} of the connector switch, which may be accomplished in several different ways.

If at the end of the conversation the called subscriber hangs up first both sides of the line will be grounded, and the relay M^{25} which is on the ground or dry side of the battery will drop back, the relay M^{27} which is on the wet side of the battery will be held up. This will energize the release magnet M^{23} over the following circuit: ground in

the preceding switch, wiper a^4 , contact m^9 , wire 95, wire 10, release magnet M^{23} wires 11, 12, 13, back contact 14, spring 15, wire 16, forward contact 17, spring 18, wires 19, 5 105, battery B and ground. This will operate the release relay M^{23} and release the connector switch and also the release relay of the preceding switch in series therewith in the usual way.

10 In case the calling party hangs up, momentarily grounding both sides of his line, the relay m^{18} being on the grounded side of the line will be deenergized and close its contacts while the relay M^{20} will 15 remain energized thus closing its contacts and release relay M^{23} will be energized over the circuit as before up to wire 12, thence by wire 20, contacts 21, 22, wire 23, contacts 24, 25, wires 26, 105, battery and ground. 20

25 In the event that the called subscriber did not answer or was busy then the relays M^{21} and M^{22} would be connected to the opposite sides of the lines and the calling subscriber hanging up would ground both sides of the line energizing relays M^{21} and M^{22} thus closing the release circuit by wire 27, spring 28, contact 29, wire 30, contact 31, spring 32, wire 26, 105, battery and ground thus 30 releasing the switches as before.

35 Having thus described my invention, I claim:

1. In a telephone exchange system, the combination with a central exchange, of 35 sub-stations connected therewith through telephone lines, a connecting circuit at the central exchange, a source of ringing current at the central exchange normally disconnected from the connecting circuit, a relay controlling the connection of said source with the connecting circuit, a second relay controlling the circuit for said first relay, an interrupter means in said circuit for periodically causing closure of said circuit 40 to periodically cause action of the first relay to connect the source with the connecting circuit and with a line connected therewith, substantially as described.

50 2. In a telephone exchange system, a calling and a called subscriber's line, a link circuit having switch terminals for interconnecting them and an automatic connector switch operating in connection with said terminals, a ringing relay actuated 55 when the connector switch has selected the terminals of a called line to connect a ringing generator with said called line only, together with an intermittent circuit closer adapted to close the circuit of said relay and 60 actuate the same at intervals, and means controlled by the called subscriber for disabling said relay when the call is answered, substantially as described.

65 3. In an automatic telephone system, the combination with a plurality of normally

open instrument circuits each provided with signaling devices, a connector switch comprising terminals for said lines and having wipers coöperating therewith which serve to connect one, a calling circuit, with another a 70 called circuit, and mechanism for operating the wipers, of a source of current for signaling purposes comprising a circuit which is normally disconnected from the instrument circuit, a signalling relay which is intermittently operated and controls contacts which open the calling end of the line and connect the signalling circuit to the called end thereof automatically upon the cessation of movement of the switch wipers. 75

4. In an automatic telephone system, the combination with a plurality of normally open instrument circuits each provided with signaling devices, a connector switch comprising terminals for said lines and having wipers coöperating therewith which serve to connect one, a calling circuit, with another a called circuit and mechanism for operating the wipers, of a source of current for signaling purposes comprising a circuit which is normally disconnected from the instrument circuit, a signalling relay which is intermittently operated and controls contacts which open the calling end of the line and connect the signalling circuits to the 85 called end thereof automatically upon the cessation of movement of the switch wipers and another relay adapted to be operated when the called instrument circuit is closed and while the signalling circuit is disconnected therefrom to render the signalling 90 relay inoperative.

5. In a telephone system a telephone line to be called, a connecting circuit for establishing connection with said line, a bridge 105 across the conversation strands of said connecting circuit, a relay and a battery in said bridge, a ringing generator, a ringing relay adapted when actuated to sever the conversation strands of said connecting circuit and 110 connect said ringing generator with the calling end thereof, a continuously operating interrupter brought into circuit with said ringing relay in response to the connection of said connecting circuit with said line, said 115 bridged relay having contacts controlling the circuit of said ringing relay and interrupter, said bridged relay being energized over the called telephone line when said line is closed at its substation and when said 120 ringing relay is in its normal condition to cause interruption of the circuit of the ringing relay and thus prevent the further actuation of said interrupter from connecting said generator with the called line. 125

6. In a telephone system a telephone line, a link circuit having terminals for connection with said line, a ringing generator, a ringing relay for connecting said generator with said line, a continually operating cir- 130

cuit interrupter, a disabling relay having normally closed contacts in the circuit of said ringing relay and said circuit interrupter, a battery, and a relay connected between 5 said battery and said line during the non-actuation of said ringing relay and operated upon the response of the called subscriber to close the circuit of said disabling relay and thus interrupt the circuit of said ringing 10 relay.

7. In a telephone system a telephone line, a link circuit having terminals for connection with said line, a ringing generator, a ringing relay for connecting said generator 15 with said line, a continually operating circuit interrupter, a disabling relay having normally closed contacts in the circuit of said ringing relay and said circuit interrupter, a battery, a relay connected between 20 said battery and said line during the non-actuation of said ringing relay and operated upon the response of the called subscriber to close the circuit of said disabling relay and thus interrupt the circuit of said ringing 25 relay, and means to prevent reringing the called subscriber at the termination of the conversation.

called subscriber reopens his line at the termination of his conversation.

8. In a telephone system a telephone line, a link circuit having terminals for connection with said line, a ringing generator, a ringing relay for connecting said generator with said line, a continually operating circuit interrupter, a disabling relay having normally closed contacts in the circuit of 30 said ringing relay and said circuit interrupter, a battery, a relay connected between 35 said battery and said line during the non-actuation of said ringing relay and operated upon the response of the called subscriber to 40 close the circuit of said disabling relay and thus interrupt the circuit of said ringing 45 relay, and means to prevent reringing the called subscriber at the termination of the conversation.

In testimony whereof, I have hereunto set my hand this 12th day of November, 1910.

CHARLES LANE GOODRUM.
